UNITED STATES PATENT OFFICE.

ALFRED SMITH, OF BIRMINGHAM, ENGLAND.

KNITTING-PIN AND THE LIKE.

1,183,250.

Specification of Letters Patent. Patented May 16, 1916.

Application filed April 13, 1915. Serial No. 21,071.

To all whom it may concern:

Be it known that I, ALFRED SMITH, a subject of Great Britain and residing at Ingleside, Livingstone Road, Handsworth, Birmingham, England, manufacturer, have invented certain new and useful Improvements in Knitting-Pins and the like, of which the following is a specification.

This invention relates to knitting pins and has for its object to provide a light article constructed in a simple manner and being most effectual.

According to this invention the knitting pin has a tubular body part with a solid acting end or point or with a tubular end, and is preferably provided with a rotatable or rigid enlarged head at the rear.

The invention is described with reference to the accompanying drawings in which:—

Figure 1 is a vertical section of a knitting pin constructed according to one form of my invention. Fig. 2 is an elevation of a modified form showing the members disassembled. Fig. 3 is a vertical section of a further modification.

Referring to Fig. 1, the body 1 is made from solid drawn tube in any suitable metal or material. The acting end or point 2 is solid and is provided with a rabbeted shank 3 fitting in the tubular body 1 and thereby brazed to, or pressed in, the tubular body 1. The rear head 4 is fitted in the body 1 by drilling a hole in the shank 5 which is then expanded against the sides of the tubular body 1.

In a modified form shown in Fig. 2, the shanks 3^a and 5^a are screwed to engage

with screw threads on the interior of the body 1.

With the modified form represented in Fig. 3, the body 1 and acting end 2 are formed in one tubular piece. The rear head 4 is formed with a stub shank 5^b having an annular groove 6 with which engages a suitable projection on the inside of the body 1. The said head may therefore be rotatably or rigidly secured to the body 1.

It is to be understood that any one of the heads may be replaced by one of the others by suitably forming the lower end of the tubular body 1 to receive the particular head. The shank of the head may be brazed to the tubular body in some cases.

What I claim as my invention and desire to secure by Letters Patent, is:—

1. A knitting needle comprising a tubular body portion, a solid tapered end section having a rabbeted portion fitted into one end of the tubular body portion, the said tapered end section being secured into position, and a head portion inserted into the opposite end of the tubular body and secured thereto.

2. A knitting needle comprising a tubular body portion, a solid head portion inserted in one end of the tubular member and a solid tapered end in the opposite end of the tubular portion.

In testimony whereof, I affix my signature in the presence of two witnesses.

ALFRED SMITH.
